AIRSHIP MOORING-MAST GEAR

Application filed November 26, 1927, Serial No. 235,850, and in Great Britain December 4, 1926.

This invention relates to improvements in airship mooring masts and more particularly to improvements in mooring masts of the type comprising telescopically moving elements of which the outer element is mounted in 5 gimbals.

An object of the invention is to provide a mooring mast of this type which will provide a variable recoil resistance with controllable 10 terminal resistance as the airship is being moored.

A further object is to provide self centering means for the mast.

Other objects will hereinafter appear.

In accordance with a principal feature of 15 the present invention the inner element or tube of the mast is formed with a piston movable in the outer element or tube as a cylinder and the upward and downward movement and the recoil of the inner tube due to 20 yawing and other movement of the airship is controlled by difference in pressure of fluid pressure medium supplied above and/or below the piston. The pressure medium employed may be gaseous e. g. air, or liquid e. g. 25 oil or water.

In accordance with a further feature of the invention the downward movement of the inner tube is used to actuate the mast centering means.

Another further feature consists in the arrangement of the pulleys over which the main haul rope is passed in mooring the airship such that the swinging of the mast produces 35 no substantial alteration in length of such main haul rope. A still further feature resides in the provision of locking means for locking the mast in centered position.

The invention is illustrated by way of example in the accompanying drawings, in which

Fig. 1 is a vertical section through a tower head and mooring mast showing one form of mooring mast constructed in accordance with 45 the invention and arranged for pneumatic control and showing means for locking the mast in centered position.

Figs. 2, 3 and 4 are detail views to a larger scale of various arrangements of the locking 50 means.

Fig. 5 is a side elevation of the tower head of a modified arrangement of the mooring mast.

Fig. 6 is a vertical section through the mooring mast shown in Fig. 5.

Fig. 7 is a vertical cross section of a tower head and mooring mast similar to Fig. 1, but illustrating a modified arrangement of the mast centering means.

Throughout the several figures of the drawings like reference numerals are used to indicate like parts.

Referring particularly to Fig. 1 of the drawings, the outer tube 1 of the mooring mast is supported in gimbals 1' in the usual manner in the frame 2 which is rigidly connected to the tower structure 3. The inner tube 4, which is formed with a piston 4^a working in the outer tube 1 as a cylinder, is fitted at its outer end with the usual arrangement of cup 4^b to receive the nose of the airship and is provided at its inner or lower end with an extension or tail rod 5 passing through a gland or stuffing box 6 and having at its lower extremity a cushioning device or spring 7 interposed between a shoulder on the tail rod and a crosshead 8 which is carried by the latter. The crosshead 8 is fitted with pulleys 9 hinged thereto and over which pass ropes 10 anchored at one end suitably to the outer tube at points spaced around the tube and connected at the other end to centering crossheads (not shown) of known construction symmetrically arranged with respect to the mast and slidably in vertical guides (not shown) in the tower supporting structure. Such crossheads are equipped in known manner with shock absorbing springs compressible by the crossheads when in their highest position and with abutments.

Associated with the piston rod 4 and cylinder 1 are high and lower pressure air reservoirs or hydraulic accumulators 20 and 21 which are connected with a cylinder above 95 and beneath the piston 4^a by means of flexible or walking pipes 22. The supply of fluid pressure medium above and below the piston 4^a and the supply of pressure medium to the means for locking the mast in centered 100

position are controlled by a control valve located in a central cabinet 23^a.

The means for locking the mast in centered position comprises a spigot member 17^a provided on the tail rod 5 and a socket member 17 mounted on a piston 18 movable within a cylinder 19 carried by the mast supporting structure, the socket 17 being movable into engagement with the spigot member 17^a by the supply of pressure medium to the cylinder 19.

The spigot 17^a and cylinder 19 are formed with a central bore through which the airship mooring rope is passed when the airship is moored to the mast.

The main haul rope 13' which passes down through the hollow piston rod 4 and extension or tail rod 5 and is passed around a large pulley 13 supported in a bracket at the lower end of the mast is passed thence around pulleys 14, 15 and 16 and thence to the ground. The pulley 14 is mounted on the one gimbal frame and the pulley 16 on the second gimbal frame. As a result of this arrangement of the rope guides 14 and 16, the swinging movement of the mast does not cause any pulling action on the main haul rope.

In the modified form of locking means shown in Fig. 2, the coned spigot 17^a is carried by an extension of the crosshead 8 and the socket or cup 17 is movable into engagement therewith in the manner described with reference to Fig. 1.

The locking means shown in Fig. 3 is similar to that shown in Fig. 2 but the cup or socket member 17 is stationary and the spigot member moves into contact therewith. The locking means shown in Fig. 4 is similar to that shown in Fig. 1 but the cup or socket member 17 is, in this instance, stationary.

Assuming the mast is in the position taken when the airship is moored, fluid pressure medium is admitted between the piston 4^a and the bottom of the outer tube or cylinder 1. As the piston 4^a rises, the spigot 17^a on tail rod 5 releases itself from the socket 17 and the concomitant upward movement of the crosshead 8 releases the centering ropes 10 until at a position approximately half way of the stroke of the piston, the swinging system is free to move without constraint of the centering gear.

As the piston 4^a moves upward in the outer tube or cylinder, the fluid pressure medium is exhausted from the upper side of the cylinder and the piston in the "out" position is free to be pulled over to any angle required by the line of approach of the airship.

It being assumed that the pull of the airship has caused the swinging system to take up a position at an angle to the vertical defined by the pull, the mooring operations proceed as follows:

The main haul rope is wound in until the airship cone is caused to enter the cup 4^b at the

outer end of the inner tube where it is automatically held in known manner. Thereafter, piston 4^a is caused to move downwards in the cylinder 1 either by the admission of the fluid pressure medium above it, or by continuing to pull the main haul rope, exhaust of the working fluid below the working piston 4^a being of course permitted to take place.

Where a hydraulic medium is used for operation of the mast, increased flexibility of recoil may be obtained by providing within the hydraulic accumulator a pneumatic dash pot device supplied with air at any desired pressure, the dash pot being so disposed as to interpose a cushion of air between the accumulator weights and the piston operated by the fluid discharge from the cylinder of the swinging system on the down stroke.

When the piston 4^a has moved a sufficient distance downwards to engage, through the medium of its tail rod or extension 5 and springs or cushioning device 7, the crosshead 8, its motion is transmitted by the crosshead to the centering ropes 10 and the swinging system is then constrained by the centering ropes 10 passing over the pulleys 9 into the central vertical position. The movement of the centering ropes 10 causes the centering crossheads to rise until they meet the abutments between which, and the centering crossheads, springs or other cushioning devices 7, will normally be interposed.

When the downward motion of piston 4^a acting through the interposed crosshead 8, centering ropes 10 and pulley 9, has caused the system to take up a vertical central position, continued motion downwards of the tail rod or extension piece brings the spigot end of the tail rod 5 into engagement with the cup or socket 17.

The fluid pressure medium preferred is air supplied at two different pressures from reservoirs 20 and 21. As an example, the air pressure in high pressure reservoir 20 may be 100 lbs. per square inch, and in the low pressure reservoir 21 may be 25 lbs. per square inch.

A reducing valve 26 between the high pressure reservoir 20 and the low pressure reservoir 21 maintains in the low pressure reservoir a pressure sufficient to push the piston outwards and to give a recoil resistance to the piston of any desired amount. If a rapidly increasing recoil resistance is required, a non-return valve (not shown) at the lower end of the cylinder or outer tube 1 is allowed to operate, but if a gradual recoil resistance be required, then the non-return valve is held off its seat in suitable manner and the low pressure reservoir then becomes a portion of the clearance space below the piston 4^a in the working cylinder 1.

The use of differing pressures of air has the following advantages:

On the upstroke of piston 4^a in the outer

tube or cylinder 1, only sufficient pressure is necessary to overcounter-balance the weight of the piston rod 4 and its accessories. On the downward stroke of piston 4^a in cylinder 1, air at higher pressure is supplied, acting against the resistance of the upward pull of the airship, and at approximately midway of its stroke against the resistance of the system of centering.

10 A cushioning effect to the pumping motion of the ship's nose is also given in a useful manner by the use of the low pressure below the piston. The employment of high pressure air for checking downward motion 15 would increase the resistance to downward motion too rapidly. This will be clear from a consideration of the inclination of an air pressure curve commencing with say 25 lbs. per square inch—which is a pressure of the 20 order which we propose to employ—as compared with an initial pressure of say 100 lbs. per square inch and the terminal pressure resultant therefrom.

Furthermore, the use of relatively low 25 pressure air from outward motion, has the advantage that the low pressure reservoir can be supplied with pressure medium by a reducing valve between it and the high pressure reservoir.

30 In the construction shown in Figs. 5 and 6, the inner tube 4 is provided at its inner or lower end with an extension or tail rod 31 passing through a gland or stuffing box 6 and having at its lower extremity a cushioning device or spring 32 interposed between it and a crosshead 33 which is movable in guides 34 on the outer tube. The crosshead 33 is fitted with pulleys 9 over which pass ropes 10 anchored at one end suitably to the 35 outer tube at points spaced around the tube and connected at the other end to centering crossheads 11 of known construction, symmetrically arranged with respect to the mast and slid able in vertical guides 11^a in the tower supporting structure. Such crossheads 11 are equipped with shock absorbing 45 springs 12, compressible by the crossheads when in their highest position, and with abutments 25.

50 The supply of fluid pressure medium above and below the piston and the supply of pressure medium to the means for locking the mast in centered position are controlled by a control valve or control valves 22^a, 22^b 55 located in a control cabinet or cabinets 23^a, 23^b

The means for locking the mast in centered position comprises a socket member 35 provided on an extension of the outer tube and a 60 spigot member 36 mounted on a piston 37 movable within a cylinder 38 carried by the mast supporting structure, the spigot 36 being movable into engagement with the socket member 35 by the supply of pressure medium 65 to the cylinder 38.

With the piston 4^a and the tail rod 31 in the lowest or innermost position shown, the spring 32 will be compressed between the tail rod and the crosshead 33. At the same time the extension 35 of the outer tube will be locked by means of the spigot 36 making connection between the moving system and the rigid structure. 70

To extend the mast, pressure medium is supplied beneath the piston 4^a from the low pressure reservoir 21. 75

As the piston 4 rises, the crosshead 33 is caused to rise also in its guides by the pull of the ropes 10 owing to the weight and thrust of the springs 12 and of the centering crossheads 11. The crosshead 33 rises until it meets an abutment 24 on the outer tube (corresponding to the position of pulley 9 indicated in dotted lines) at which time the crossheads 11 are sufficiently far from their abutments 25 to allow the desired swinging movement of the mast. 80

When the piston has been drawn down by the amount of free recoil, which normally will be half the full stroke of the piston, the extension or tail rod 31 engages through the medium of spring 32 with the crosshead 33 and pushes the latter downwards and this movement of the crosshead 33, transmitted through pulleys 9 and ropes 10, causes the 90 crossheads 11 to rise and pulls the mooring mast into the central or mooring position. During this operation, the centering crossheads 11 are gradually lifted until they engage through the medium of springs 12 with 95 their abutments 25. The locking spigot 36 is then moved into engagement with the socket 35 and the mast locked in centered position. 100

In the construction of mooring mast shown in Fig. 7 which is similar to that shown in Fig. 1, the crosshead 8 is movable on the tail rod or extension 5 and there is provided, in association with the moving crosshead 8, a piston 26^a working in a cylinder 27 connected by a pipe 28 with a port 29 in the main cylinder 1, the supply of pressure fluid to the cylinder 27 and the consequent centering movement of the crosshead 8 by the piston 26^a associated therewith, being permitted on the main piston 4^a uncovering such port near the 105 end of its downward travel. Although a single cylinder 27 is shown, two or more cylinders symmetrically disposed around the outer tube or cylinder 1 may be provided. The cylinder or cylinders 27 may be independently supplied by pressure medium and may 110 exhaust otherwise than through the pipes 28. 115

We claim:—

1. An airship mooring mast comprising two telescoping elements, means on one of 125 said elements to receive a part of an airship, and fluid pressure means causing relative movement between said elements.

2. An airship mooring mast comprising a cylinder and a piston movably mounted there- 130

piston rod, piston and tail rod, means for centering said mast, and means for locking said mast in centered position.

15. A mooring mast comprising a cylinder mounted on gimbals, a piston disposed in said cylinder and having a piston rod extending from one end thereof and a tail rod from the other end thereof, means on the end of said piston rod to receive a part of an airship, a haul rope passing through said piston rod, piston and tail rod, means for centering said mast, and means for locking said mast in centered position, said locking means comprising a piston having a socket to receive the end of said tail rod.

15 16. An airship mooring mast comprising two telescoping elements movable with respect to each other, means on the inner element to receive a part of an airship, means 20 to cause relative movement between said elements, gimbals supporting said outer element and consisting of two gimbal frames, pulleys mounted on each of said frames, and a haul rope running over said pulleys 25 and adapted to be connected to said airship.

17. A mooring mast comprising a cylinder mounted on gimbals, a piston disposed in said cylinder and having a piston rod extending from one end thereof, and a tail rod from the other end thereof, fluid pressure means to operate said piston, means on the end of said piston rod to receive a part of an airship, and means to engage said tail piece to hold it in desired position.

35 18. A mooring mast comprising a cylinder mounted on gimbals, a piston disposed in said cylinder and having a piston rod extending from one end thereof and a tail rod from the other end thereof, fluid pressure 40 means to operate said piston, means on the end of said piston rod to receive a part of an airship, means to engage said tail piece to hold it in desired position, a plurality of 45 pulleys on said tail piece, a corresponding number of centering crossheads, and ropes connecting said crossheads to said cylinder and running over said pulleys.

19. A mooring mast mounted on gimbals and comprising a tail rod, means to center said mast, means to hold the mast in centered position comprising a piston movable into and out of engagement with said tail rod, and fluid pressure means to operate said piston.

55 ARCHIBALD HALL-BROWN.
EDWIN WALTER JONES.
